UNITED STATES PATENT OFFICE.

HENRY M. VETTERLEIN, OF PHILADELPHIA, PENNSYLVANIA, ASSIGNOR OF ONE-HALF TO HENRY PENN BURKE, OF PHILADELPHIA, PENNSYLVANIA.

LADDER.

Application filed July 29, 1924. Serial No. 728,840.

To all whom it may concern:

Be it known that I, HENRY M. VETTERLEIN, a citizen of the United States, residing at Philadelphia, in the county of Philadelphia and State of Pennsylvania, have invented certain new and useful Improvements in Ladders, of which the following is a specification.

The object of my invention is to provide a ladder of novel construction employing wooden, upright rails and transverse, step bars formed of sheet metal, which shall be inexpensive, strong and durable.

The invention aims to provide a ladder which may be constructed by unskilled persons from upright rails and step bars formed in accordance with my invention; and the parts of which may be readily disassembled, reassembled, and substituted for like parts in constructing other ladders.

With the foregoing and related objects in view, my invention consists of the elements and the combinations of them hereinafter described and claimed.

25 In the accompanying drawings, illustrating the invention,

Figure 1 is a front view of a portion of a ladder embodying my invention.

Figure 2 is a vertical section thereof, on line 2—2 of Fig. 1.

Figure 3 is a horizontal section of the ladder on line 3—3 of Fig. 1.

Figure 4 is an end view of one of the step bars, enlarged.

35 Figure 5 is a front view of a modified form of the invention.

Figure 6 is a horizontal section of the modified form, on line 6—6 of Fig. 5.

Referring first to Figs. 1 to 4, inclusive, 40 4 designates two spaced parallel, upright rails which may be formed of any suitable material, preferably wood, and which, as herein illustrated, are rectangular in cross section.

45 5 designates the step bars, each of which is formed of sheet metal and comprises an elongated body portion 7 having flanges or ribs 8 formed on the longitudinal edge portions thereof, and having projections 9 formed thereon, the body portion 7, flanges or ribs 8 and projections 9 all being formed of a single blank of sheet metal.

55 In forming the flanges or ribs 8 the longitudinal edge portions of the blank from which the bar is formed are bent, at 10, to

extend forwardly from the body portion 7, bent, at 11, to extend toward each other, and bent, at 12, to extend back toward the body portion and to diverge from each other, as clearly shown in the drawings, providing 60 strong stiffening flanges or ribs for the body portion, which will resist strain in all directions.

The projections 9 are struck from the body portion 7 and bent to extend rearwardly 65 therefrom in parallel and spaced relation to each other and at right angles to the longitudinal stiffening flanges or ribs 8.

The body portion 7 and the projections 9 are provided with holes or openings 13 and 70 14, respectively, for the reception of fastening devices for securing the step bars 5 to the rails 4, as will be presently described.

The projections 9 of the step bars 5 serve as spacers for the rails 4 while the parts of 75 the ladder are being assembled, and, thereafter, they retain the rails in spaced parallel relationship; and the rearward surfaces of the body portions 7 of the bars 5 engaging the forward surfaces of the rails 4 hold 80 the parts firmly together and prevent forward or backward displacement of the rails 4 relatively to each other from their parallel relationship.

Any suitable fastening devices may be 85 employed to secure the step bars 5 and the rails 4 together. For this purpose, as herein illustrated, I employ lag screws 15 which penetrate the body portion 7 and projections 9 through the openings 13 and 14 therein, respectively, and which are screwed into the rails 4, as shown in the drawing. These screws 15 may be readily removed without injury to the parts of the ladder when it is desired to disassemble them.

95 The rails 4 may be of any desired length and any desired number of the step bars 5 may be employed to provide a ladder of any desired length.

In the modification shown in Figs. 5 and 100 6, I employ a single, central located upright rail 16 and step bars 17 having the central portions of the body portions thereof engaged with the forward surface of the rail 16 and having the end portions thereof projecting outwardly from the respective sides of the rail 16. The step bars 17 have projections 18 which extend rearwardly from the body portions thereof and embrace the rail 16. The body portions of the bars 17 110

and their projections 18 are secured to the rail 16 by lag screws 19. The longitudinal edge portions of the bars 17 have upper and lower stiffening flanges 20 and 21 formed thereon, and the outer end portions of the lower flanges 21 diverge upwardly toward the outer ends of the upper flanges 20 to strengthen the outer or free end portions of the bars 17.

10 I claim as my invention:—

1. In a ladder, an upright rail, a step bar extending transversely thereof and comprising an elongated body portion formed of sheet metal and seated against the forward surface of the rail, and having a forwardly extending stiffening flange formed on one of its longitudinal edge portions and having a projection bent to extend rearwardly from the body portion and engaging one of the lateral surfaces of the rail, and fastening devices penetrating the body portion of the bar
- 15 2. In a ladder, an upright rail, a step bar extending transversely thereof and comprising an elongated body portion formed of sheet metal and seated against the forward surface of the rail, and having a forwardly extending stiffening flange formed on one of its longitudinal edge portions and having a projection struck from the body portion of the bar intermediate its ends and intermediate its longitudinal edges and extending rearwardly from the body portion and engaging one of the lateral surfaces of the rail, and fastening devices penetrating the body portion of the bar and the projection and entering the rail and securing them together.

and the projection and entering the rail and securing them together.

2. In a ladder, an upright rail, a step bar extending transversely thereof and comprising an elongated body portion formed of sheet metal and seated against the forward surface of the rail, and having a forwardly extending stiffening flange formed on one of its longitudinal edge portions and having a projection struck from the body portion of the bar intermediate its ends and intermediate its longitudinal edges and extending rearwardly from the body portion and engaging one of the lateral surfaces of the rail, and fastening devices penetrating the body portion of the bar and the projection and entering the rail and securing them together.

In testimony whereof I affix my signature hereto.

HENRY M. VETTERLEIN.
